Primary Examiner — T Chase Nelson*Assistant Examiner* — Jonathan J. Han(74) *Attorney, Agent, or Firm* — Cohen IP Law Group, PC; Michael N. Cohen(57) **CLAIM**

I claim the ornamental design for a grip attachment, as shown and described.

DESCRIPTION

FIG. 1 is a perspective view of the grip attachment;

FIG. 2 is a front view of FIG. 1;

FIG. 3 is a back view of FIG. 1;

FIG. 4 is a left view of FIG. 1;

FIG. 5 is a right view of FIG. 1;

FIG. 6 is a top view of FIG. 1; and,

FIG. 7 is a bottom view of FIG. 1.

The broken lines in the drawings illustrate portions of the grip attachment that form no part of the claimed design.

1 Claim, 7 Drawing Sheets(56)
